RING FORMING MACHINE

Julius Jorgensen, Detroit, Mich., assignor to F. L. McLaughlin, Detroit, Mich.

Application June 26, 1939, Serial No. 281,085

17 Claims. (Cl. 140—55)

This invention relates to ring forming machines and has for its primary object to provide a portable machine having means for poising a hog ring to enable insertion thereof to the point of use, having power actuated means for closing a ring so poised, and having means which automatically functions after closing of one ring to form another hog ring and to place it in a poised position.

10. Hog rings, or in other words, open ring-like wire formations which might loosely be defined as C-shape, are placed over elements to be connected together and are then bent to form a closed ring. They are used quite commonly in the 15. spring industry, for example, to connect coil springs together and to a marginal frame. According to the usual practice the hog rings are pre-formed by a separate machine and are inserted, by hand, into a hog ring tool, which is 20. then operated to close the ring-like formation. As a distinction over this present day practice this invention has for its main object to provide a machine which automatically forms and poises a hog ring after each ring closing operation 25. thereof.

Due to the manner in which a hog ring tool must be handled it is essential that it be of comparatively light weight and that it be very compact to enable use thereof in close quarters.

30. Accordingly, it is another object of this invention to construct and correlate the power actuated mechanisms necessary to both close and form hog rings, in such manner that the machine is very light in weight and of such compact nature that 35. it may be readily handled to enable use of the hog rings in very close quarters.

Another object is to provide a machine in which the wire stock from which the hog rings are formed is fed in one end and the hog rings 40. are poised at the other end, to thus enable pointing of the machine in the nature of a gun in inserting a poised hog ring to the point of use. In other words, greater convenience in handling the machine is obtained by poising the hog ring in 45. line with the wire stock being fed into the machine than would be the case if the ring were poised in any other direction, and the mechanism is designed to provide this desirable characteristic.

50. Another object is to provide a portable hog ring forming and closing machine operable by a flexible cable from a remote source of power and having a manually controlled clutch for operating the machine at will.

55. Another object is to provide a machine em-

bodying means for feeding measured lengths of wire-like stock thereinto, and for severing the stock prior to each bending operation thereof. In this connection, a more specific object is to provide clamping means for holding the stock against movement at the time the stock is severed and at all times except when the feeding means is operative.

Another object is to provide a pair of relatively movable power actuated jaws for bending a hog ring into closed form, and means automatically rendered operative after each bending operation for forming another hog ring and placing it in a poised position between the jaws. The forming means comprises a pivoted forming head about 10 which the stock is bent, and is located between the jaws so that formation of the new hog ring takes place between the jaws. In this respect another more specific object is to cause relative separation between the forming head and the 15. completely formed hog ring, in order that by operation of the movable jaws the hog ring may be bent into its closed position.

Another object is to provide a machine embodying a feed disc for feeding a measured length 25. of stock with each rotation thereof, and a manually operable clutch for starting movement of the disc and for automatically stopping rotation thereof. During each rotation of the disc it first causes operation of the bending jaws to close a 30. poised hog ring, secondly it feeds a measured length of stock, thirdly it causes actuation of the stock severing means, it then causes actuation of the stock bending means to form a hog ring and, finally, it places the hog ring just formed 35. in a poised position in readiness for the closing operation which is the first step in the next cycle.

Other objects and advantages will become more fully apparent as reference is had to the accompanying drawings wherein my invention is illustrated, and in which:

Fig. 1 is a side elevation of the machine with the housing in section to expose the mechanism,

Fig. 2 is a plan view, with the housing similarly broken away,

Fig. 3 is a side elevation of the stock severing mechanism, illustrating its position at the completion of the severing operation,

Fig. 4 is a fragmental section illustrating the coacting cutters of the stock severing means,

Fig. 5 is an elevation of the forming mechanism, illustrating its position immediately prior to the start of the forming operation,

Fig. 6 is similar to Fig. 5, and illustrates the forming operation partially performed,

Fig. 7 shows the forming mechanism at the completion of the forming operation,

Fig. 8 shows the forming mechanism on its return stroke, and the next supply of stock fed thereinto,

Fig. 9 is a view looking in the direction of the line 9-9 of Fig. 8, and illustrating the manner in which the bending element on the forming head brushes past the stock which has already been fed,

Fig. 10 is a side elevation of the hog ring closing or bending jaws, showing the jaws in the position where the hog ring has just been formed,

Fig. 11 is an end section corresponding to Fig. 10, but showing the forming head which is omitted from Fig. 10,

Fig. 12 is a side elevation of the jaws, illustrating the first step in the operation thereof during which the upper jaw moves the upper end of the hog ring off the forming head,

Fig. 13 is an end section, corresponding to Fig. 12, but showing the forming head which is omitted from Fig. 12,

Fig. 14 is an end section showing the forming head in a position separated from the hog ring,

Fig. 15 is an elevation of the bending jaws, illustrating the ring closing position thereof,

Fig. 16 is a detail of the control clutch, and

Fig. 17 is a cross-section of the control clutch.

Referring first to Figs. 1 and 2, 1 designates a supporting member comprising a plate of fairly heavy stock having a sheet metal enclosing housing 2 suitably mounted thereon. The housing 2 is so shaped that it may be conveniently grasped in the hand of an operator in order that the hog rings formed and poised as hereinafter described may be conveniently inserted to the place of use.

Stock feeding and severing means (Figs. 1 to 4)

40 The stock feeding and severing means is shown in Figs. 1 to 4, and comprises a disc 3 rotatably mounted on the supporting member 1. The disc 3 has a circumferentially grooved portion 4 of greater diameter than the remainder of the disc, and constituting a stock feeding means.

Pivotedly mounted at 5 on the supporting member 1 is an arm 6 having a roller 7 mounted thereon and a spring 8 acting on the outer end of the arm to bias upward movement thereof. 50 Wire-like stock 9 passes between the disc 3 and the roller 7, and when the grooved portion 4 of the disc 3 contacts the stock the latter is advanced a distance equal to the length of the portion 4. It is apparent, therefore, that with each 55 rotation of the disc 3 the stock 9 is advanced a measured amount.

When the high portion 4 of the disc 3 contacts the stock it presses the latter downwardly against the roller 7, and the roller 7 causes the arm 6 to swing downwardly from the position shown in Fig. 3 to that shown in Fig. 1. The arm 6 has a stock engaging portion 10 which normally presses the stock against a serrated jaw 11, fixed on the supporting member 1, to hold the stock against accidental movement. When the arm 6 is swung downwardly, as above described, the stock may pass freely between the engaging portion 10 and the jaw 11.

70 Mounted in the supporting member 1 for rotative movement is an element 12 having a cutting edge 13 normally positioned as shown in Fig. 1 in order that the stock 9 may be moved thereunder. The stock in being fed under the cutting edge or movable cutter 13 passes over a station-

ary cutter 14 which is secured to the supporting member 1.

The rotatively movable element 12 has a notch 15 in the periphery thereof and into which an arm 16 on a lever 17 extends. The lever 17 is 5 pivotally supported by a pin 18 mounted on a rocker arm 19, and in this connection it is pointed out that the rocker arm has no function as far as the severing mechanism is concerned other than to support the lever 17. The rocker arm 19 is a part of the hog ring forming mechanism hereinafter described and in order to form a machine of very compact nature the lever 17 is mounted on the rocker arm rather than on a 10 separate supporting bracket.

The end of the lever 17 projects to a point adjacent the disc 3 and has a lug formation 20 engageable by a projection 21 on the disc. When engaged by the projection 21 the lever 17 is swung downwardly and the arm 16 moves the 20 movable cutter 13 as shown in Fig. 3 to cause severance of the stock. After severance of the stock the lever 17 is restored to its original position by a spring 22.

Ring forming means (Figs. 1, 2 and 5 to 9)

The forward extremity of the supporting member 1 has a stationary jaw 30 over which the stock 9 is fed as it is advanced as above described. 30 Rotatably mounted at 31 in the supporting member 1, adjacent and above the jaw 30, is a forming head 32 which might loosely be described as being heart shape. A bending member 33 is formed on the side of a gear 34 which is rotatably and slidably mounted on a shaft 35 carried by the forming head 32, and a spring 36 acts between a washer 37 and the gear 34 to hold the gear pressed against the side of the forming head 32. An arcuate rack 38 is formed on the supporting member 1 and is engaged by 40 the gear 34 in such manner that the bending member 33 is caused to rotate about its shaft 36 as the forming head 32 is swung about its support 31.

A connecting rod 39 is pivotally attached to 45 the forming head 32 at 40 and has its other end attached to the projection 21 on the stock feeding disc 3. Therefore, as the feeding disc 3 is rotated the forming head 32 is swung back and forth on its support 31. Fig. 5 illustrates the 50 position, approximately, at the beginning of the bending operation, in which position a severed length of stock 9 resides above the stationary jaw 30, beneath the forming head 32, and has the bending element 33 therebeneath. As the 55 forming head 32 moves through the position shown in Fig. 6, the forming head 32 and the stationary jaw 30 coact to bend one portion of the stock, and the forming head 32 and the bending member 33 coact to bend another portion. 60 The stock is thus bent into a hog ring, which might loosely be defined as C shape, and which is referred to herein and in the claims as an open ring-like formation.

After the stock 9 has been formed into an open 65 ring-like formation, it is shifted laterally to remove it from the forming head in order to enable the forming head to return to the position shown in Fig. 5 for a repetition of the forming operation. The means for performing this function 70 is a part of the ring bending and closing means hereinafter described. Assuming, however, that the ring has been shifted laterally from a position encircling the forming head to the position alongside the forming head shown in Fig. 9, it 75

will be noticed that another piece of stock 9a has been fed into position at this stage of the operation. The piece of stock 9a is, therefore, in the path of the bending member 33 as it returns 5 from the position shown in Fig. 7 to the position shown in Fig. 5, a condition which is illustrated in Figs. 8 and 9. For this reason the bending member 33 has an inclined edge 41 which engages the stock 9a and slidably shifts the gear 34 on its shaft 35 to enable the bending member to move to a position beneath the stock.

Ring bending or closing means (Figs. 1, 2 and 11 to 15)

15 Mounted at 50 on the supporting member 1 is a rocker arm 19, mentioned above in connection with the support of the lever 17. The rocker arm 19 has a projecting portion 51 engageable with a stop 52 on the supporting member 1 to restrict working movement thereof in one direction, and has an end portion 53 engageable with the projection 21 on the feeding disc 3.

20 The other end 54 of the rocker arm is inclined, and has an arm 55 pivoted at 56 thereon, and having stops 57 and 58 for restricting pivotal movement thereof. On the extremity of the arm 55 is a jaw 59 and a spring 60 normally yielding holds the arm 55 with its stop 57 in engagement with the rocker arm end 54.

25 When the rocker arm 19 is in the position shown in Fig. 10, the jaw 59 is in engagement with the open ring-like formation 9b which has just been completed on the forming head as above described, and the projection 21 on the feeding disc 3 is just about to engage the rocker arm end 53. As the projection 21 engages the end 53, the rocker arm is rocked from the position shown in Fig. 10 to that shown in Fig. 12, and causes the rocker arm end 54 to lower. The 30 jaw 59 is at this time in engagement with the open ring-like formation 9b which holds it against downward movement with the result that relative pivotal movement takes place between the arm 55 and the rocker arm end 54. This 35 results in lateral shifting of the jaw 59 from the position shown in Fig. 11 to that shown in Fig. 13, and causes the upper end of the ring-like formation to be moved off the upper end of the forming head 32.

40 On the end of the rocker arm 53 which is engaged by the projection 21 on the feeding disc 3 is a portion 61 shaped to cause a dwell in the movement of the rocker arm. That is, the projection first engages the rocker arm end 53 and causes movement from the position shown in Fig. 10 to that shown in Fig. 12, and then as the projection 21 travels along the portion 61 the rocker arm remains stationary. Comparison of Fig. 12 with Fig. 8 illustrates that the forming head moves rapidly at the time the projection 21 is in engagement with the dwell causing portion 61, and during this movement it acts like a cam against the tilted ring-like formation 9b to shift the bottom portion thereof laterally. The 45 open ring-like formation 9b is thus positioned between the jaws 30 and 59, free from the forming head 32, and in readiness for the bending or closing operation.

46 This is the stage in the cycle of operation 50 where the machine comes to rest, or, in other words, the cycle of operation is so controlled by means hereinafter described that the cycle starts with the open ring-like formation poised between the jaws 30 and 59.

55 As the rocker arm 19 is moved from the posi-

tion shown in Fig. 12 to that shown in Fig. 15 the jaw 59 coacts with the stationary jaw 30 in bending the ring-like formation into a closed ring.

5 During movement of the rocker arm 19 as above described the lever 17 which is supported thereon will shift slightly, but is held against material shifting by engagement with the cutter supporting element 12. Once the ring-like formation is compressed, the projection 21 clears 10 the rocker arm end 53, and the jaws 30 and 59 may be pulled away from the closed ring. Engagement of the projection 21 with the lug 20 on the lever 17, with the arm 16 in engagement with the cutter supporting element 12, 15 causes restoration of the rocker arm 19 to the position shown in Fig. 10.

20 It will be noted that the jaw 59 in the position shown in Fig. 11 normally would interfere with bending of the stock about the forming head, 25 from the position shown in Fig. 6 to that shown in Fig. 7. Due to the inclination of the rocker arm end 54 and the pivoted arm 55, the jaw 59 moves laterally as it moves upwardly, and therefore as the stock engages the arm 55 and 30 moves it upwardly it shifts the jaw 59 laterally to a position similar to that shown in Fig. 13. After the stock is completely bent, the spring 60 moves the jaw 59 into engagement with the formation 9b, as shown in Figs. 10 and 11.

Operating means and control (Figs. 1, 2, 16 and 17)

35 It becomes apparent from the foregoing description that with each rotation of the feeding disc stock is advanced into the machine, is severed, then formed into an open ring-like formation, poised for use, and bent into a closed ring. This cycle is so arranged that the machine comes to rest with the open ring-like formation poised 40 and upon operation of the control first closes the ring formation and then continues to operate through the different stages until another ring-like formation is poised, at which time it automatically comes to rest.

45 Associated with the feeding disc 3, but rotatable with respect thereto, is a worm gear 70 adapted to be constantly rotated by means of a gear (not shown) operated by a flexible cable 71 from a remote source of power. The worm 50 gear 70 has a bore 72 in which a stem 73 on the disc 3 extends, and pivoted in the stem 73 is a dog 74 adapted to engage in any one of a plurality of notches 75 in the adjacent face of the gear 70. A spring 76 biases movement of the 55 dog 74 in a direction to engage the notches 75, and with the dog 74 in engagement with one of the notches the disc 3 is caused to rotate with the gear 70.

60 Pivoted at 77 on the supporting member is a trigger-like control lever 78 having an arm 79 thereon formed with a cam-like stop portion 80 on the extremity thereof. A spring 81, mounted on the lever support 77, normally holds the lever 78 and arm 79 in a position where the cam-like 65 end 80 is in the path of movement of the dog 74.

65 Figs. 16 and 17 show the gear 70 and above described clutch at one stage in their movement, or, in other words, the clutch mechanism is engaged, and it is pointed out that the view 70 Fig. 16 is taken from the side opposite to which Fig. 1 is taken, with the result that the gear 70 moves counterclockwise as viewed in Fig. 16. As the dog 74 is moved with the gear 70, it finally engages the cam-like end 80 of the arm 75.

79 and the latter withdraws the dog from the notch 75 with which it is in engagement. This is the stage in the cycle of the machine at which the open ring-like formation is poised.

5. When the lever 78 is manually pivoted, the arm 79 moves in the direction of the arrow 82, allowing the dog 74 to engage the face of the gear 70 and to thereafter engage in the first notch 74 to present itself. A plurality of notches 10 74 are provided in order that the clutch may be engaged without waiting for more than a fraction of a revolution of the gear 70. Regardless of which notch is engaged, however, the disc 3 15 may only make one complete revolution and will then be automatically stopped if the control lever is released. Release of the control lever 78 is not essential to the operation, however. The machine will continue to form and close the rings as long as the control lever is compressed 20 and in the case of an operator sufficiently skillful to insert a poised ring to the point of use during the short period it is poised the machine may be operated continuously.

The particular construction and correlation of 25 the several parts and mechanisms above described results in a machine of light weight and very compact nature, and although it constitutes the preferred arrangement, it will be understood, of course, that various changes may be made 30 within the scope of the appended claims without departing from the spirit of the invention, and such changes are contemplated.

What is claimed is:

1. In a hog ring machine, a pair of relatively 35 movable members adapted to hold a pre-formed open ring-like formation in a poised position and operable to bend the formation into a closed ring, means disposed laterally of said members for forming a length of wire-like stock into an open 40 ring-like formation, and means for moving a formed open ring-like formation laterally from the forming means and for placing it in a poised position between said members.
2. In a hog ring machine, a pair of relatively 45 movable members adapted to hold a pre-formed open ring-like formation in a poised position and operable to bend the formation into a closed ring, means for forming a length of wire-like stock into an open ring-like formation, means for moving a 50 formed open ring-like formation from the forming means and for placing it in a poised position between said members, and means for subsequently operating said members, said forming means and said last named means.
3. In a hog ring machine, a pair of relatively 55 movable members adapted to hold a pre-formed open ring-like formation in a poised position and operable to bend the formation into a closed ring, means for forming a length of wire-like stock into an open ring-like formation, means for feeding measured lengths of stock to said forming means, means for moving a formed open ring-like formation from the forming means and for placing it in a poised position between said members, operating 60 said means for subsequently operating said members, said feeding means, said forming means and said ring-like formation moving means, and automatic means for rendering the machine inoperative immediately after operation of said formation moving means.
4. In a ring forming machine, means for feeding 65 stock, means for severing the stock in measured lengths, means for forming a severed piece of stock into an open ring-like formation, bending 70 means for receiving the formed ring-like forma-

tion and operable to bend said formation into a closed ring, and means for causing relative separation of the formation and the forming means to enable bending of the formation by the bending means.

5. In a ring forming machine, means for feeding stock, means for severing the stock in measured lengths, means for forming a severed piece of stock into an open ring-like formation, bending means for receiving the formed ring-like formation and operable to bend said formation into a closed ring, means for causing relative separation of the formation and the forming means to enable bending of the formation by the bending means, and means for causing cyclic operation of the 10 several means with operation of the bending means being the first step in the cycle and the operation of the forming means being the last step.

6. In a ring forming machine, a plurality of 20 correlated elements mounted on a common support and comprising ring bending means, ring forming means, ring transferring means for transferring a ring from the forming means to a position for bending by the bending means, and 25 means for causing cyclic operation of all of said means with the first step in the cycle comprising operation of the ring bending means, the second step of the cycle comprising operation of the ring forming means, and the final step in the cycle 30 comprising operation of the transferring means.

7. In a ring forming machine, a plurality of correlated elements mounted on a common support and comprising ring bending means, ring forming means, stock feeding and severing means, 35 ring transferring means for transferring a ring from the forming means to the bending means, and means for causing cyclic operation of all of said means with operation of the bending means the first step in the cycle, operation of the feeding 40 and severing means second, operation of the forming means third and finally operation of the ring transferring means.

8. In a hog ring machine, a main support having a fixed jaw thereon, a rocker arm mounted on 45 said support and having a jaw thereon coacting with the fixed jaw in poising a pre-formed open ring-like formation, the second jaw being movable incident to rocking movement of the rocker arm to close said ring-like formation, means for forming 50 an open ring-like formation between said jaws, and means for rocking the rocker arm and for subsequently operating said forming means with each operation thereof.

9. In a hog ring machine, a main support having a fixed jaw thereon, a movable jaw mounted on said support and coacting with the fixed jaw in poising a pre-formed open ring-like formation and movable relative to the fixed jaw to bend said formation into a closed ring, a forming head 60 pivoted on said support and having a portion coacting with the fixed jaw for bending a piece of stock interposed therebetween incident to pivotal movement of the forming head, a bending element on said forming head, means for moving said 65 bending element incident to pivotal movement of said forming head to bend said stock about another portion of the forming head to complete the formation of an open ring-like formation, and means for causing relative separation between the 70 forming head and the completed open ring-like formation to enable bending of said formation into a closed ring by movement of said movable jaw.

10. In a hog ring machine, a main support 75

- having a fixed jaw thereon, a movable jaw mounted on said support and coacting with the fixed jaw in poising a pre-formed open ring-like formation and movable relative to the fixed jaw 5 to bend said formation into a closed ring, a forming head pivoted on said support and having a portion coacting with the fixed jaw for bending a piece of stock interposed therebetween incident to pivotal movement of the forming head, means 10 for feeding measured lengths of stock between said forming head and jaw, a bending element on said forming head, means for moving said bending element incident to pivotal movement of said forming head to bend said stock about 15 another portion of the forming head to complete the formation of an open ring-like formation, and means for causing relative separation between the forming head and the completed open ring-like formation to enable bending of said 20 formation into a closed ring by movement of said movable jaw.
11. In a ring forming machine, an actuating member movable through a predetermined cycle with each operation thereof, manual means for 25 controlling the operation of said member, means operated by said member for feeding a measured length of wire-like stock at a predetermined stage in the cycle thereof, stock severing means operatively connected to said member and operable at a predetermined stage in the cycle thereof to 30 form the stock into an open ring-like formation, a pair of relatively movable jaws so disposed that the ring-like formation is poised therebetween, and means operatively connecting the jaws to 35 said member for operating said jaws at a predetermined stage in the cycle thereof to bend 40 said formation into a closed ring.
12. In a ring forming machine, an actuating member movable through a predetermined cycle with each operation thereof, means operated by said member for feeding a measured length of 45 wire-like stock at a predetermined stage in the cycle thereof, stock severing means operatively connected to said member and operable at a predetermined stage in the cycle thereof to sever the stock, forming means operatively connected 50 to said member and operated thereby at a predetermined stage in the cycle thereof to form the stock into an open ring-like formation, a pair of relatively movable jaws so disposed that the ring-like formation is poised therebetween, 55 and means operatively connecting the jaws to said member for operating said jaws at a predetermined stage in the cycle thereof to bend said formation into a closed ring, and a control for 60 manually starting the cycle of operation of said member and for automatically stopping said member.
13. In a ring forming machine, an actuating member movable through a predetermined cycle with each operation thereof, means operated by 65 said member for feeding a measured length of wire-like stock at a predetermined stage in the cycle thereof, stock severing means operatively connected to said member and operable at a predetermined stage in the cycle thereof to sever 70 the stock, forming means operatively connected
- to said member and operated thereby at a predetermined stage in the cycle thereof to form the stock into an open ring-like formation, a pair of relatively movable jaws so disposed that the ring-like formation is poised therebetween, 5 means operatively connecting the jaws to said member for operating said jaws at a predetermined stage in the cycle thereof to bend said formation into a closed ring, and a control for manually starting the cycle of operation of said member and for automatically stopping said member at a stage in its cycle subsequent to 10 operation of the forming means and prior to operation of the jaws.
14. In a ring forming machine, an actuating member movable through a predetermined cycle with each operation thereof, manual means for controlling the operation of said member, means operated by said member for feeding a measured length of wire-like stock at a predetermined stage in the cycle thereof, stock severing means operatively connected to said member and operable at a predetermined stage in the cycle thereof to 15 sever the stock, forming means operatively connected to said member and operated thereby 20 at a predetermined stage in the cycle thereof to form the stock into an open ring-like formation, a pair of relatively movable jaws so disposed that the ring-like formation is poised therebetween, means for causing relative separation between the forming means and the formed open 25 ring-like formation, and means operatively connecting the jaws to said member for operating said jaws at a predetermined stage in the cycle thereof to bend said formation into a closed ring. 30
15. In a ring forming machine, a pair of relatively movable jaws adapted to hold a pre-formed open ring-like formation in a poised position and operable to bend the formation into a closed ring, a feed disc for feeding wire-like stock between the jaws, stock severing means operated by said feed disc, and means for bending a severed piece of stock into an open ring-like formation and for disposing it between said 40 jaws. 45
16. In a ring forming machine, a pair of relatively movable jaws adapted to hold a pre-formed open ring-like formation in a poised position and operable to bend the formation into a closed ring, a feed disc for feeding wire-like stock between the jaws, stock holding means rendered operative and inoperative by said feed disc, stock severing means operated by said feed disc, and means for bending a severed piece of stock into an open ring-like formation and for disposing it 50 between said jaws. 55
17. In a ring forming machine, a pair of relatively movable jaws adapted to hold a pre-formed open ring-like formation in a poised position and operable to bend the formation into a closed ring, a feed disc for feeding wire-like stock between the jaws, stock severing means operated by said feed disc, means for bending a severed piece of stock into an open ring-like formation and for disposing it between said jaws, and 60 means for causing relative separation between a formed open ring-like formation and the bending means to enable the jaws to bend said formation into a closed ring. 65
